JOSEPH VAN STEENKISTE AND JOSEPH VAN MAERCKE, OF WEVELGHEM, BELGIUM.

SCUTCHING MACHINE.

Application filed March 12, 1924, Serial No. 698,703, and in Belgium March 20, 1923.

The present invention relates to a scutching machine of the type with scutching cylinders arranged in pairs and turning in opposite directions and which are combined with a conveying device feeding the material to be scutched from one end of the machine to the other one between the said cylinders.

None of the known machines has ever been able to scutch flax in the way of the Flemish scutching, that is to say to beat, peel and shed it and this owing to the rigidity of the spokes or arms bearing the scutching knives and to the fact that the material to be scutched was prevented from hanging freely between the cylinders.

The object now of the present invention is to provide a real scutching machine, scutching the flax as perfectly as can be done by hand or by means of the so called "Flemish scutching mill."

For this purpose the knives are placed on the scutching cylinders in such a way that the knife on one cylinder begins to act upon the material to be scutched only when the knife of the other cylinder which works in an opposite direction has reached its lowest working position, in other words the knives are placed in such a manner that only one of them acts at a time on the freely hanging material.

The blades or knives and the scutching board or stock must be adjustable in order to enable the scutchers to adjust the blades, that is to say, to bring the cylinder nearer to the board or to move it off, according to the nature of the flax to be worked.

The blades must be able to effect a peeling action, their function being to extract the broken ligneous stem from the fibrous ribbon. This is obtained by the rapid beating of the blades producing a bend or crease in the loose flax thus enabling them to enter between the stem and the fibrous ribbon.

The number of the blades must be in proportion with the speed of the cylinder so that the blow of the knives be neither too hard nor too soft, because in the first instance they shorten the flax by cutting the ends and reducing them to dust, and in the second case only the upper part of the knives is operative.

The blades must have a certain breadth as they must produce a flattening effect from the edge to the back, thus be able to flatten

the crease in the flax as would a smoothing iron, in order to prepare the flax for the next blow.

The machine being the object of the present invention unites all of these conditions.

Its principal features are the following:

It combines sets of scutching cylinders with devices for maintaining the flax to be scutched and conveying it through the machine between the scutching cylinders and devices for placing it horizontally when it leaves a first set of cylinders, to turn it over and so to have it scutched the other way by a second set of cylinders or to place it in position ready to be taken out of the machine after having left for instance the second set of cylinders.

The number of scutching blades mounted on each cylinder is so small and the diameter of the cylinders so great, that the flax will hang loosely between the cylinders and that but one knife or blade will act, at a time, on the flax.

The breadth of the knives is such that they will peel with their cutting edge and flatten with their sides.

The cylinders are adjustable, by approaching them to each other or moving them away from each other by means of set-screws.

The flax is placed in the proper position for the knives to act upon by an arched grill made up with laths.

The devices for feeding, conveying and returning the flax comprise systems of pressure belts and guide belts running lengthwise and conveying the flax between the sets of cylinders, and belts provided with laths travelling transversely thereto, taking up the loosely hanging part of the scutched flax from one of the systems of belts travelling longitudinally placing it horizontally and bringing it over with the scutched end to the other system of belts travelling longitudinally and another belt provided with laths travelling transversely thereto, taking the freely hanging scutched part of the flax up and placing it horizontally ready for being taken out of the machine.

The longitudinally travelling belts have an outer rubber surface preventing the blows of the knives from pulling out the flax laying between the rubber surfaces. One of the said surfaces has a prominence formed thereon registering with a groove formed in the corresponding surface of the other belt.

The rubber layers are fixed on a linen or cotton envelope enclosing the steel belts.

The supporting guide belts travel on supporting rollers while the pressure belts are pressed on the guide or supporting belts by means of yielding rollers and the supporting rollers are arranged in such a way that each pressing roll presses the pressing belt on the supporting belt between two supporting rollers.

One form of execution of the object of the invention is shown diagrammatically and by way of example in the annexed drawings.

Fig. 1 is a front view of the machine partly broken away.

Fig. 2 is a side view of a modified form of a scutching cylinder partly broken away.

Fig. 3 is a front or end view of one set of scutching cylinders and of one of the longitudinal flax transporting devices.

Fig. 4 is a partial longitudinal section of a scutching cylinder.

Fig. 5 is a plan view of a modified form of scutching knife 4^a with a plane cutting edge.

Fig. 6 is a transverse section of the knife of Fig. 5.

Fig. 7 is a longitudinal section of the machine with but one set of scutching cylinders on line 7-7 of Fig. 1.

Fig. 8 is a plan view on line 8-8 of Fig. 1.

Fig. 9 is a plan view on the middle line 9-9 of Fig. 1.

Fig. 10 is a vertical elevation of the maintaining, feeding and conveying device.

Fig. 10^a shows two of the pressure rollers 55, 56 and their supports on an enlarged scale.

Fig. 10^b shows the supports for the pressure and the guiding rollers in section on an enlarged scale.

Fig. 11 is a plan view illustrating the arrangement of the longitudinal and transverse feed belts 37, 37' and 68, 68'.

Fig. 12 is a vertical end view of a pair of scutching cylinders associated with a longitudinal conveying belt.

Fig. 13 is a vertical section through a longitudinal conveyor showing a transverse conveyor in side elevation.

Fig. 14 is a vertical section similar to Fig. 13 but showing a transverse conveyor oppositely disposed to that shown in Fig. 13.

The machine, as shown, comprises frames 1, 1', 1², 1³ devices for maintaining and conveying the flax through the machine, and sets of scutching cylinders 2 and 3, and 2' and 3'. Each cylinder, 2, 3, 2' and 3' is provided with knives or blades, 4, 4', 4^a, 4^b longitudinally extending over the respective cylinders. Each knife or blade is mounted on an arched arm or spoke, 5, 5' or 5^a respectively. These arms which are of steel and have a certain elasticity, or may be rendered elastic by any known means, are fixed

on a shaft 6, enclosed in a wooden cylinder 7, enclosed itself in a wooden cylinder 8. Each blade or knife 4, 4', 4^a is provided with holes such as 7' to fix them on the arms or spokes 5, 5' and 5^a by means of bolts, not shown. The knives or blades 4, 4', 4^a are adjustable, that is to say, their inclination on the arms 5, 5' or 5^a may be regulated.

An arched grill 10, Fig. 2 catches the freely hanging part of the flax during the rapid rotation of the cylinders 2 and 3. This grill is made up with wooden or steel laths as 11, 12, 13, 14, 15, 16, the inner faces of which are rounded. The flax is prevented by these grills from being rolled around the scutchers when these scutchers reach its ends, and is thus kept in the right position for receiving the proper blow of the scutcher. The sharp edge of each knife protrudes about 50 c/m. from the grill 10.

The flax is maintained and guided through the machine and returned therein by means of belts.

Fig. 7 shows this device as being applied to a machine with two sets of scutching cylinders 2, 3 and 2', 3'.

The first pair of cylinders 2, 3 is shown as being driven by means of slack chains 19 and 20 and a toothed wheel 21 fixed on the main shaft 22 and meshing with the toothed wheels 23 and 24 fixed on the axes of the sprocket wheels 25 and 26 respectively.

The main shaft 22 drives a toothed wheel 27 by means of a worm 28, while on the shaft of worm gear 27 are fixed two sprocket wheels, only one of which, 29, is shown. One of the sprocket wheels 29 drives by means of a chain 31 a pulley 32 through the intermedium of a sprocket wheel 33 fixed thereon. The other sprocket wheel drives a pulley 34 provided with a sprocket wheel 35 by means of a chain 36. The pulley 32 drives one system of maintaining and conveying belts 37, 38 and the pulley 34 drives the system of maintaining and conveying belts 37', 38'. The construction of the maintaining, conveying and returning belts cooperating with the set of cylinders 2 and 3 being identical with the one cooperating with the set of cylinders 2' and 3', only the one cooperating with the former one will be described in detail.

The conveying belt 37 is guided on pulleys 32, 39, 40, 41. The shaft of each of the pulleys 32 and 41 is journaled in a vertical plate 42 fixed by means of a bracket 43 to the standard 1² of the machine and the shaft of each of the pulleys 39 and 40 is journaled in a plate 44 fixed to the standard 1 by means of brackets 45 and 46. The pressure belt 38 runs on two pulleys 47 and 48, the shafts of which are journaled in brackets 49 and 50 fixed respectively to standards 1 and 1². The upper part of the conveying belt 37 is supported between the pulleys 40 and 41 by

means of rollers 51, 52, 53 to n rotating in a hollow bar 54 on pins 54^a. One end of the bar 54 is fixed to the standard 1 and the other one to the standard 1². On the lower 5 part of the belt 38 press rollers 55, 56, 57 to n , supported from a bar, one end of which is fixed to the standard 1 while the other end is fixed to the standard 1². Each roller 55, 56, 57 to n rolls between two pins 10 58^a in cups 58. Springs 59, 60, 61 to n act upon the rollers 55, 56, 57 to n . The pressure rollers 55, 56, 57 to n and the supporting rollers 51, 52, 53 to n are mounted in such a way that one of the said pressure rollers 15 always acts between two of the said supporting or guide rollers. The belt 37 which is driven by the pulley 32 in the direction of the arrows 62, drives the belt 38 by friction in the direction of the arrows 63.

20 Both of the belts 37 and 38 which are of steel are lined with cotton or linen, on which linings are fixed layers of rubber 64 and 65 respectively.

The rubber layer 64 of the lower belt 37 25 has a longitudinal prominence 66 adapted to engage with the longitudinal groove 67 of the upper belt 38. The flax to be scutched is so firmly clamped at one end between these two belts 37 and 38, owing to the prominence 30 66 and to the groove 67, that it is not pulled out by the blows of the scutching knives.

The loosely hanging part of half scutched flax leaving the first said pair of belts 37 35 and 38 is received by the belt 68 travelling transversely to the belts 37 and 38. This belt 68 which is provided, on its outer face, with laths 69, travels on pulleys 70 and 71 of which the first one is fixed on the shaft of the scutching cylinder 3 and the other one on a 40 special shaft not shown.

The flax string 72 on reaching this belt 68, takes the horizontal position until it has 45 passed the pulley 71, when the scutched end of this string 72 hangs down loosely and is taken up by the belt 37' of the second system of belts 37', 38'. This belt 37' carries this end along under the belt 38' and the other half of the string 72 will be scutched by the second set of scutching cylinders 2' 50 and 3'. When leaving these belts 37' and 38' the flax 72 is taken up by the belt 64' travelling transversely thereto and may be taken out of the machine. The second conveying and returning system being identical with the former one, the same reference characters 55 have been used except for the driving pulley which is numbered 35 and that all the others are provided with an index (').

The shaft of the scutching cylinders 2' 60 and 3' may be driven in the same way as those of the cylinders 2 and 3.

Set screws 73 and 74 (Fig. 1) serve to adjust the cylinders 2 and 3, and identical screws are provided for setting the cylinders 65 2' and 3'.

The invention is not limited to the particular form of execution described and shown, as anybody skilled in the art is able of modifying constructional details without departing from the spirit of the invention. 70

Having now fully described our invention what we claim and desire to secure by Letters Patent is:

1. In a scutching machine, the combination with sets of scutching or swinging cylinders each turning in opposite directions of sets of longitudinally conveying flexible steel belts, lined with a woven material, a layer of longitudinally grooved rubber on the lining of one of the belts of each said set and a layer of rubber having a longitudinal projection on the lining of the other belt of the said set in engagement with the grooves in the first mentioned rubber layer, and of a transversely travelling returning 85 flexible steel belt cooperating with each of the said sets of conveying belts and provided on the outer face with perpendicularly arranged parallel laths. 90

2. In a scutching machine, the combination with sets of scutching or swinging cylinders, each set turning in opposite directions, of sets of longitudinally conveying flexible steel belts lined with a woven material, a layer of longitudinally grooved rubber on the lining of the lower belt of each set and a rubber layer having a longitudinally extending projection on the lining of the upper belt of each set being adapted to engage with the groove of the rubber layer in the said lower belt, and a transversely travelling returning flexible steel belt cooperating with each set of longitudinally conveying belts provided on the outer face with perpendicularly arranged parallel laths. 100

3. In a scutching machine, in combination with sets of scutching cylinders, a set of conveying and pressure belts cooperating with each set of said scutching cylinders, a returning belt travelling transversely thereto 110 cooperating with each set of said conveying and pressure belts, a common driving shaft for the sets of scutching cylinders, the sets of conveying and pressure belts and the said returning belts, a common driving shaft extending longitudinally throughout the machine, means to drive the said shaft on one of its ends, means on both ends of the said shaft to drive the sets of said scutching cylinders, a rotatable shaft bearing each scutching cylinder, means on the outer end of each of the said shafts to drive them and a power transmission member yieldingly connecting the shaft of each scutching cylinder to the common driving shaft, a driving pulley for each said returning belt, fixed on the shaft of one of the scutching cylinders of each set with which the said returning belt cooperates, driving means for the driving pulleys of the sets of conveying and pressure belts, com- 115 120 125 130

prising a pinion on the main driving shaft, a toothed wheel meshing with the said pinions, two sprocket wheels fixed on the shaft of said toothed wheel, a driving pulley for 5 each said set of conveying and pressure belts, a sprocket wheel fixed on the shaft of each said driving pulley, a driving chain connecting each of the sprocket wheels of the said driving pulleys with the corresponding 10 sprocket wheel on the shaft of the said toothed driving wheel.

4. In a scutching machine, the combination with sets of longitudinally conveying belts, each cooperating with a transversely 15 extending returning belt, of sets of scutching cylinders turning in opposite directions, each cylinder having curved arms longitudinally extending scutching blades arranged 20 on said arms, so that in each set of cylinders only one blade will act at a time upon the material to be treated, and a longitudinally extending arched grill fixed to each series of 25 arms bearing a scutching blade close to this blade adapted to prevent the free end of the material from being rolled round the blades owing to their action on same.

5. In a scutching machine in combination, sets of longitudinally travelling conveying 30 flexible steel belts, a transversely travelling flexible steel belt cooperating with each set of the said conveying belts, as many sets of conveying belts as there are sets of scutching cylinders, each cylinder comprising a metal shaft, a noise absorbing cylinder on the 35 metal shaft, rows of curved arms fixed on this sleeve and a second noise absorbing

sleeve over the first sleeve through which protrude the said arms, longitudinally extending knives, one on each row of arms, means for guiding the flax between the 40 cylinders, and an arched longitudinally extending grill fixed to each row of said arms beneath the knives fixed on each row of arms.

6. In a scutching machine, the combination with longitudinally extending conveying belts, a transversely extending returning belt adapted to return the fibers from one longitudinally extending belt to another longitudinal belt with scutching cylinders operating in association with each of said longitudinally extending belts. 45

7. In a scutching machine, a scutching cylinder comprising a shaft, a noise absorbing sleeve enclosing the shaft and forming the 55 hub of the cylinder, a plurality of rows of curved arms mounted on the noise absorbing sleeve, a second or outer noise absorbing sleeve over the first sleeve, a longitudinally extending scutching knife mounted on each 60 row of curved arms and longitudinally extending laths mounted on the curved arms of each row of arms adjacent each scutching knife constituting an arched grill adapted to prevent the fibers under treatment from rolling around the blade under the action of the 65 blows given by same.

In testimony whereof we affix our signatures.

JOSEPH VAN STEENKISTE.
